UNITED STATES PATENT OFFICE.

WALTER W. A. KRUCK, OF CAMDEN, NEW JERSEY.

VENT CLEANER FOR PIANO PLAYERS.

Application filed October 19, 1920. Serial No. 417,983.

To all whom it may concern:

Be it known that I, WALTER W. A. KRUCK, a citizen of the United States, residing in Camden, New Jersey, have invented certain Improvements in Vent Cleaners for Piano Players, of which the following is a specification.

One object of my invention is to provide means for cleaning the vents of a piano player without dismantling the player.

A further object of the invention is to provide means whereby a series of vents can be cleaned at the same time.

A still further object of the invention is to make the vent tube and cleaner tube in one piece.

These objects I attain in the following manner, reference being had to the accompanying drawings, in which:

20 Fig. 1 is a transverse sectional view on the line 1—1, Fig. 2, illustrating my improved vent cleaner for piano players;

Fig. 2 is a longitudinal sectional view on the line 2—2, Fig. 1;

25 Fig. 3 is an enlarged sectional view showing a combined vent tube and cleaner;

Fig. 4 is a view showing a modification of the means for operating the cleaner;

30 Fig. 5 is a sectional view showing my invention applied to a piano player having three banks of unit valves;

Fig. 6 is a view showing the cleaner made separate from the vent tube and located in a different position from the device illustrated in Fig. 5; and

35 Fig. 7 is a detached perspective view of the vent tube.

Referring to the drawings, 1 is the front board of a piano player having passages 4^a therein. 2 is the primary valve box extending the full length of the player, as shown in Fig. 2. 3 are the individual primary valves. In the valve box are separate passages 4 communicating with the passages 4^a, and the valves 3 control the air to these passages. 5 is a vacuum chamber common to all of the valves. 6 are separate passages leading to the vacuum chamber from pipes 7 opening at the tracker bar 8 from which the perforated paper 9 is passed from the roll 10 to the roll 11.

12 are diaphragms between the chamber 5 and the passage 6. In a passage 13 are vents 14 having exceedingly small vent

openings 15. The main object of the invention is to provide means for keeping the vent openings clear at all times.

The vent 14 is in the form of a tube, as shown in Fig. 3, and extends through the partitions 16 and the lower wall 17 of the primary valve box. The tube is cut away at 18 so as to allow air to flow from the passage 6 into the vent and through the vent opening 15. In the lower portion of the vent tube is a plunger 19 from which extends a stem 20 pointed at its outer end and arranged to pass into and through the vent opening 15 so as to clear the vent opening of any foreign matter that may be retained therein.

21 is a partition formed in the vent tube and the stem passes through this partition, as shown in Fig. 3, and has a disk 22 thereon, closing the passage through which the stem extends when the cleaning device is out of action. Mounted between the partition 21 and the plunger 19 is a coiled spring 23, which retracts the plunger and its stem when released from the operating mechanism. There is one of these devices for each key. They may be operated by hand individually, but it is preferable to operate them in unison through the medium of a longitudinal bar 24, which is located under all of the plungers 19. The bar 24 rests on arms 26 of levers 25 pivoted at 27 to brackets 28 secured to the board 29. The levers 25 are connected to an operating bar 30 which is attached to an arm 31 of a bellow 32 operated by a pneumatic key at the key board through the tube 33, Fig. 2. Other means of operating this bar 30 may be devised without departing from the essential features of the invention.

In Fig. 4, a bar 30^a is shown, which extends through the side frame 34 of the piano player, provided with a push button 35 by which it can be moved longitudinally to actuate all of the plungers 19.

In Fig. 5, I have illustrated a series of 100 primary valve boxes 2^a. There is one box for each note of the piano. The boxes are preferably arranged in tiers, as shown. 3^a is the valve. 12^a is the diaphragm. 14^a is the vent having a vent opening at the end. 19^a is the plunger to which is attached the stem for cleaning the vent. 24^a are three longitudinal bars, which operate the plun-

gers. 25^a are levers, which actuate the bars 24^a. These levers are controlled by rods 30^a in the manner shown in Fig. 2.

In Fig. 6, I have illustrated a slight modification of the vent, in which the vent tube 14^b is separate from the tube 14^c containing the plunger 19^b. The device is located in the primary valve box 2^b at a different point from that shown in Fig. 5. The plunger 10 and spring are similar in construction to the plunger and spring illustrated in Fig. 3. The plunger illustrated in Fig. 6 is in such position that it can be actuated by removing a front board from the player piano.

15 In operating a piano player, the perforated music roll, which is passed over the tracker bar 8, is made of paper and the friction removes particles of fibre from the paper. These particles, in time, collect in 20 the vent openings and prevent the proper operation of the mechanism. It has been customary to dismantle a portion of the mechanism so that access could be had to the vent openings.

25 By my invention the vent openings can be cleaned without dismantling the player and without the necessity of calling in a skilled workman to perform the operation.

I claim:

30 1. The combination of a piano player having an air passage with a vent located in the passage and having a small opening at one end; a cylinder located in an extension of the passage; a plunger mounted in the 35 cylinder and having a stem extending through the end of the cylinder and close to the opening in the vent; and a spring lo-

cated in the cylinder to retain the plunger, and its stem, clear of the vent, said plunger being in such a position that it can be pushed 40 into the cylinder to allow its spindle to pass through the opening in the vent.

2. The combination in a vent cleaner for piano players, of a cylinder; a plunger in the cylinder; a stem secured to the plunger 45 extending through the end of the cylinder; a disk on the stem outside of the cylinder; and a spring located on the cylinder, between the inner end of the plunger and an extension thereon, by which the plunger is 50 pushed into the cylinder.

3. The combination in a piano player, of a series of valve boxes having independent passages; a vent in each passage; a plunger located opposite each vent and having a 55 stem arranged to be projected through a vent opening; a spring for retracting each plunger; a longitudinal bar extending past all of said plungers; an operating bar; levers between the two bars whereby, on the 60 longitudinal movement of the operating bar, the other bar will move the plungers; and a single mechanism actuating the operating bar.

4. In a combined vent and cleaner for 65 piano players, the combination of a tube reduced at one end and perforated at said end and open at the opposite end; lateral openings in the tube; a partition; a plunger projecting into the open end of the tube and 70 having a stem arranged to pass through the vent opening; and a spring between the plunger and the partition.

WALTER W. A. KRUCK.
